UNITED STATES PATENT OFFICE

122,175

DESIGN FOR AN EGG HOLDER

Louisa P. Wagner, New York, N. Y.

Application May 21, 1940, Serial No. 92,489

Term of patent 7 years

To all whom it may concern:

Be it known that I, Louisa P. Wagner, a citizen of the United States, residing at the city of New York, Borough of the Bronx, Bronx County, in the State of New York, have invented a new, original, and ornamental Design for an Egg Holder, of which the following is a specification, reference being had to the accompanying drawing, forming a part thereof.

In the drawing:

Fig. 2 is a side elevational view, and
Fig. 3 is a top plan view thereof.

I claim:

The ornamental design for an egg holder, as shown.

LOUISA P. WAGNER.
